UNITED STATES PATENT OFFICE

103,289

DESIGN FOR AN AEROPLANE

Johannes H. Wendt, Chicago, Ill., assignor of
one-half to Mart E. Lee, Chicago, Ill.

Application January 25, 1935, Serial No. 55,053

Term of patent 14 years

To all whom it may concern:

Be it known that I, Johannes H. Wendt, formerly a citizen of the German Empire, having declared my intention of becoming a citizen of the United States, residing at Chicago, in the county of Cook and State of Illinois, have invented a new, original, and ornamental Design for an Aeroplane, of which the following is a specification, reference being had to the accompanying drawing, forming a part thereof, in which

Figure 1 is a top plan view of an aeroplane embodying my new design;

Fig. 2 is a front elevational view of Figure 1, showing an aeroplane having continuous wing sections;

Fig. 3 is a side elevational view thereof; and
Fig. 4 is a side perspective view thereof.

I claim:

The ornamental design for an aeroplane substantially as shown and described.

JOHANNES H. WENDT.
